COMBINATION LOCK

John Heinze, Arickaree, Colo.

Application November 17, 1937, Serial No. 174,978

4 Claims. (Cl. 70—133)

This invention relates to locks and particularly to combination locks in which a part is turned to a certain predetermined position in order to permit the lock to be opened.

One object of the invention is to provide a combination lock improved in various particulars to produce accuracy and reliability, as well as simplicity of construction and convenience of operation.

Another object of the invention is to construct a combination lock which is to be used in connection with doors, drawers, cabinets, safes, lockers and the like.

The nature of the present invention and its distinguishing features and advantages will appear as the description proceeds.

In the drawings:—

Figure 1 is a plan view of the numbered dial of a combination lock embodying the present improvement.

Figure 2 is a sectional view of the lock as applied, the section taken on line 2—2 of Figure 1.

Figures 3, 4, 5, 8, 9 and 10 are detail views of the various discs controlling the lock combination.

Figure 6 shows the mounting of the latch bolt in the lock case.

Figure 7 is a sectional view of the lock as shown on line 7—7 of Figure 2.

Figure 11 is a cross sectional view taken on line 11—11 of Figure 2.

Figure 12 is a plan view of the dial pointer.

Figure 13 shows the disc engaging flange of the slotted sleeve.

Figure 14 shows a modification of a two-bolt combination lock.

Figure 15 is a longitudinal sectional view of the lock taken on line 15—15 of Figure 14 as applied to a door.

Figure 16 is a transverse sectional view taken on line 16—16 of Figure 14.

Figure 17 is a detail sectional view of the lock comprising the latch bolt and the superimposed combination discs taken on line 17—17 of Figure 14.

In the construction shown in Figures 1 to 13, the reference character 1 designates the casing of the combination lock. Attached to the bottom plate 2 of the casing, in spaced apart relation, by bolts 3 is a disc 4, constituting the lowermost of a number of superimposed discs described in detail hereinafter.

The disc 4 is provided with a sleeve-like, upwardly extending projection 5 encircling a centrally located bore 6. A radial slot 7 extends into 55 the periphery of the disc, close to the projection 5,

while a lug 8, diametrically opposite the slot 7, bears a pivot pin 9. Also on the disc 4, on its lower face, is an arcuate enlargement 10, serving as a guide for a rectangular latch bolt 11.

The latch bolt 11 slides upon the bottom plate 2 through a fore-end opening 12, forward and back, guided by the enlargement 10 of the disc 4 on one side, and controlled by spring means 13 on the other side, one end of the spring 13 secured to the main plate 2, while its free end engages in a recess 14 of the latch bolt.

An oblong opening 15 extends longitudinally from the center of the latch bolt 11 towards the inner end thereof, it being provided with a cam notch 16 midway of the opening 15. In spaced apart relation to the opening 15, and mounted centrally upon the latch bolt 11 is a lengthwise extending lug 17, the purpose of which will be later described.

A hollow latch operating boss 18, preferably having a square cross sectional passage, is loosely inserted in the opening 15 of the latch bolt, the boss 18 being provided with a cam projection 19 engaging in the cam notch 16 of the latch bolt opening 15.

Sleeved over the boss 18 is the hub-like member 5 of the disc 4. Superimposed and adjustable with the disc 4, are a series of combination discs, as indicated in the drawings by the numerals 20, 21, 22, 23 respectively. Each of said discs, with the exception of the uppermost, is provided with arcuate slots 24 of various lengths, while central bores 25 for each disc serve to closely but loosely fit the individual discs over the hub member 5. Also each disc is provided with a corresponding radial slot 26 to fit over the lug 17. Diametrically opposite each slot 26, the discs 22, 23, are provided with peripheral extensions 27 to receive the pivot pin 9 of the lowermost disc 4.

The uppermost disc 22 is provided with a ring 28 closely but rotatably fitting over the hub member 5, and has two oppositely faced notches 29 in its inner face. Engaging the hub member 5, and consequently the latch operating boss 18, is a latch actuator or key 30 correspondingly shaped to closely fit into the bore of the latch operating boss 18, the actuator preferably being manipulated by a thumb nut 41 detachably mounted thereon. Loosely fitted over the latch actuator 30 is a sleeve 31 having slots extending from one end at opposite points.

The lower end of the sleeve 31 terminates in a flange 32 having two opposite downwardly projecting extensions 33 to engage the recesses 34 of the rim 28 of the uppermost disc 22. A metal

55

plate 36 is fixed over the customary door key opening carrying a dial plate 37 provided with a peripheral arcuate slot 38 for properly setting the dial plate 37 by a bolt 39.

5 The dial plate has a hub-like member 40 fitted over the sleeve 31 and confined in its operation between the flange 32 and an inner ring-like enlargement by a compression spring 35.

10 A sleeve 41 having its upper reduced end provided with slight inward projections is disposed over hub member 40. A pointer 42 having its ring-like body slipped over hub member 40, is held by sleeve 41 in set position, due to the pointer being provided with diametrically opposite, inwardly directed extensions 43 engaging in correspondingly arranged slots in the lower end of the sleeve 41.

15 A disc 45 engages over the slightly protruding end of sleeve 31 by engaging the slots of the sleeve 31.

20 Figures 14 to 17 inclusive, show a modified two-bolt combination lock in which the reference numeral 50 designates the casing and 51 the latch bolt. Fixed on the end of the bolt 51 is 25 a block 52; the bolt slides back and forth through the lock opening 53 upon the main plate 54 of the casing and beneath the lowermost combination disc 55, it being operated by an actuator 56 from either side of the lock.

25 Superimposed on the lowermost disc 55 are a number of discs 57, 58, 59, 60, 61, 62 each provided with a radial notch 63 extending from the periphery toward the center and adapted to fit over the block 52 of the bolt.

30 The lowermost disc 55 is provided with an arcuate enlargement on its lower face to guide the bolt in its sliding movement. The disc 55 has a peripheral extension 64 which carries an upright projection 65. An opening in the inner 35 end of the bolt, beneath the disc 55, has a cam notch, to loosely accommodate a latch operating member 66, and sleeved over the member 66 is a hub-like member 67 of the disc 55. Each of the discs, with the exception of the uppermost, is provided with arcuate slots of various lengths near the periphery, while central bores for each disc serve to closely but loosely fit the discs over the hub member 67.

35 Likewise, adjacent the radial notch, one of each pair of discs is provided with a bored peripheral extension 65 to receive the pin 65 of the disc 55. The ring 69 has two opposite notches 70 in its inner face. As the application and construction of the actuator with the lock is exactly like that described with reference to Fig-

40 sures 1-13 it is therefore deemed not necessary to describe it in detail here.

45 In the lower end of the casing 50, is a sliding latch bolt 71 having a bevelled head to contact the escutcheon plate on the door frame. It is operated by the actuator 56 in the ordinary hub 52 controlled by a pivoted lever 73 engaging the hub, which in turn actuates the inner pivoted end of the bevelled latch bolt 71.

50 Having thus described the invention, what is claimed as new and desired to secure by Letters Patent, is:—

55 1. A lock comprising a casing, a bolt slidable therein, a series of superimposed tumbler discs, the lowermost disc attached to the casing, said bolt operating below the lowermost disc, an arcuate enlargement of the lower face of said disc, a cam member controlling said bolt, an actuator for said cam member, and a dial settable by said actuator.

20 2. A lock comprising a casing, a bolt slidable therein, a series of superimposed tumbler discs, the lowermost disc attached to the casing, means on said disc for guiding said bolt, a cam member loosely seated in an opening of the bolt, a projecting hub member on said disc loosely fitting over said cam member, an actuator fitting into said cam member, and a dial settable by said actuator.

25 3. A lock comprising a casing, a bolt slidable therein, a series of superimposed discs, the lowermost disc attached to the casing, an arcuate enlargement on the lower face of said disc to guide said bolt, a spring urging the bolt against said enlargement, a cam member loosely seated in a cam slot of the latch bolt, a projecting hub on said disc loosely fitting over said cam member, an actuator fitting said cam member, and a dial settable by said actuator.

30 4. A lock comprising a casing, a bolt slidable therein, a series of superimposed tumbler discs, the lowermost being secured to the casing, said bolt movable below said disc, each of said discs having arcuate slots of unlike lengths and registerable radial slots, a block carried by said bolt 45 to engage the radial slots when in register, a cam member having a hub extension, said member seated in a notch of the bolt, a projecting hub on said disc loosely fitting over said cam member, an actuator fitting into said cam member, a slotted sleeve closely fitting over said actuator, said sleeve terminating in a flange having downturned projections, and a dial settable by said actuator.
